UNITED STATES PATENT OFFICE.

WILLIAM T. SYMONS, OF HOUGHTON-LE-SPRING, ENGLAND.

DESIGN FOR FENDER GAS-STOVE.

Specification forming part of Design No. **11,290**, dated July 8, 1879; application filed May 3, 1879.
[Term of patent 3½ years.]

To all whom it may concern:

Be it known that I, WILLIAM THOMAS SYMONS, of Houghton-le-Spring, England, have originated and designed a Design for a Fender Gas-Stove, of which the following is a full, clear, and exact description, reference being had to the accompanying drawing, making part of this specification.

The numeral 1 indicates the framing, the ends of which are joined to the front at right angles. The framing is beveled upward and inward from its base, and its front is surmounted by three short pedestals, one at each end and the other in the center. Each of these pedestals supports a ball or sphere, and these spheres are connected by rails 3. From the end spheres short rails 6, having ornamental terminals, project at right angles to the rails 3. The radiating frame bridges approximately the entire space inclosed by the framing 1, and its top plate, 2, is oblong in form, and of a length nearly equal to the length of the space within the framing, being supported by suit-

able abutments at its ends. Under the top plate, 2, longitudinally with respect to it and the framing, is arranged a gas-pipe having several burners, the flames of which may be seen between the rails 3 and the top of the framing.

The surfaces of the framing and radiating frame may be ornamented in any suitable manner.

What I claim is—

The design for a fender gas-stove, consisting of the rectangular framing 1, having its front surmounted by the pedestals supporting the spheres, which are connected by the rails 3, the short rails 6, and the oblong radiating top plate bridging the space within the fender framing, substantially as described and shown.

WILLIAM THOMAS SYMONS.
